[57] CLAIM

The ornamental design for a flight information indicator for aircraft, as shown and described.

DESCRIPTION

FIG. 1 is a front elevational view of a flight information indicator for aircraft showing my new design;
FIG. 2 is a top plan view thereof, the bottom being a mirror image thereto;

FIG. 3 is a left side elevational view thereof;

FIG. 4 is a right side elevational view thereof;

FIG. 5 is a rear elevational view thereof;

FIG. 6 is a fragmentary section on an enlarged scale as taken from line 6—6 in FIG. 1.
